DESIGN.

R. M. HAMPTON.
KNITTED FABRIC.

No. 20,111.

Patented Aug. 26, 1890

UNITED STATES PATENT OFFICE.

RICHARD M. HAMPTON, OF PHILADELPHIA, PENNSYLVANIA, ASSIGNOR TO EDWARD H. GODSHALK, OF SAME PLACE.

DESIGN FOR A KNITTED FABRIC.

SPECIFICATION forming part of Design No. 20,111, dated August 26, 1890.

Application filed July 8, 1890. Serial No. 358,063. Term of patent 7 years.

To all whom it may concern:

Be it known that I, RICHARD M. HAMPTON, a citizen of the United States, residing in the city and county of Philadelphia, State of Pennsylvania, have invented and produced a new and original Design for Knitted Fabrics, of which the following is a specification, reference being had to the accompanying photograph, forming part thereof.

The leading features of my design for a knitted fabric are alternately plain and spotted or mottled stripes on the face thereof.

In the photograph, A designates a piece of knitted fabric the face whereof is striped, one set of stripes being plain and the other mottled, said sets alternating. 15

I claim—

The herein-described design for a knitted fabric, consisting of alternating plain and spotted or mottled stripes, as shown and described. 20
